FIG. 1 is a perspective view of a whirlpool bathtub, showing my new design;

FIG. 2 is a top plan view thereof;

FIG. 3 is a side elevational view thereof;

FIG. 4 is an end elevational view thereof;

FIG. 5 is an interior view thereof, taken along the line 5-5 of FIG. 3; and

FIG. 6 is a top plan view of another embodiment of the whirlpool bathtub, the side elevational and end elevation views thereof being substantially the same as that shown in FIGS. 3 and 4, respectively.

The surface pattern which is partially shown in FIG. 6 is understood to repeat throughout the indicated areas.

I claim:

The ornamental design for a whirlpool bathtub, as shown and described.
